(57) **CLAIM**

The ornamental design for a light-emitting diode, as shown and described here.

DESCRIPTION

FIG. 1 is a perspective view of the light-emitting diode in accordance with our new design, showing an upper side with left and front sides as obliquely viewed from above;

FIG. 2 is a perspective view thereof, showing an upper side with right and front sides as obliquely viewed from above;

FIG. 3 is a perspective view thereof as obliquely viewed from bottom;

FIG. 4 is a front elevation view thereof, the rear being a mirror image of FIG. 4;

FIG. 5 is a top plan view thereof;

FIG. 6 is a bottom plan view thereof;

FIG. 7 is a left side view thereof; and,

FIG. 8 is a right side view thereof.
